UNITED STATES PATENT OFFICE

2,440,159

APPARATUS FOR DRYING THREAD BY CONDUCTION

Richard W. Stanley, Drexel Hill, Pa., assignor to
 American Viscose Corporation, Wilmington,
 Del., a corporation of Delaware

Application February 26, 1944, Serial No. 523,985

2 Claims. (Cl. 34—52)

1

This invention relates to an improved method of and apparatus for drying and collecting filamentary material. More particularly, the invention is concerned with methods of drying and collecting filamentary material under a light but constant tension which permits freedom for uniform lengthwise contraction of the filamentary material during drying thereof.

According to the usual method of manufacturing artificial filamentary material, as by the viscose method, for example, the fiber-forming material is extruded into a coagulating and regenerating bath, from which it is withdrawn as a continuous thread and collected in the form of an annulus on the surface of a bobbin, or within a centrifugal bucket. The annulus is then subjected to a number of after-treatments, such as desulfurizing, bleaching, etc., after which it is washed and dried in package form.

The drying of packages of filamentary material is generally accompanied by the development of a number of undesirable concomitants in that the different layers constituting the package tend to shrink unevenly which results in a thread of non-uniform denier.

Thread so dried is frequently found to possess varying residual shrinkage capacities along the length thereof, and varying dyeing affinities, so that knitted, woven, or otherwise fabricated materials manufactured therefrom are unsatisfactory.

One object of the present invention is to provide a method whereby running lengths of filamentary material are dried prior to collection thereof in package form and under substantially tensionless conditions or under a light but constant tension, so that it is permitted to shrink freely and uniformly throughout its length during the drying step.

Another object of the invention is to provide means for collecting dried running lengths of filamentary material and means for automatically adjusting the rate of collection to compensate for variations in tension of the material caused by the changing diameter of the package upon which the material is being wound or by any local variations in the capacity of the material to shrink under the given conditions.

According to the invention, filamentary material, preferably in the form of a bundle of filaments, twisted or untwisted, such as yarn, thread, etc., is continuously advanced through a drying zone, and thereafter passes through a loop to a winding device for collection in the form of a wound package. A tension responsive means is

2

provided which comprises a tension responsive element in the loop formed in the material at the discharge end of the drying zone and a means associated with the tension responsive element and with the driving means for the collecting device for varying the speed of the collecting device in response to a change in the position of the tension responsive element. The tension responsive means thus serves to maintain the loop in the dried material, insuring that a short length of the material remains suspended in the vicinity of the drying zone, and also serves to control, automatically, the speed at which the collecting device is driven. Any variations in the length of the suspended material are indicated by change in the position of the tension responsive element suspended in the loop, either upwardly or downwardly, which results in a corresponding decrease or increase in the speed at which the collecting device is driven.

Under optimum conditions, the thread or the like advances over or through the drying zone, through the loop, and to the collecting device under a light but constant tension which is maintained as near the zero point as possible and which is due to the weight of the short length of the material suspended in the vicinity of the drying zone, as a result of the loop formed therein, and the light weight of the tension responsive element thereon. Under certain conditions, however, the length of material suspended in the vicinity of the drying zone may be increased or decreased, with a resultant variation in the tension of the filamentary material passing through the drying zone. Thus, it may be increased due to an increase in the speed at which the filamentary material is advanced over or through the drying zone from a thread-advancing means, or it may be decreased due to the tendency of the material to shrink during drying, or as the result of an increase in the peripheral speed of the collecting device in response to a build-up of thread thereon.

In accordance with the invention, all such variations in the length of the filamentary material suspended in the vicinity of the drying zone, and thus of the tension of the material, are immediately automatically compensated for by a corresponding variation in the rate at which the dried filamentary material is collected. Thus undesired excess tension or slack of the material passing through the drying zone is immediately removed, with a resulting beneficial effect on the physical properties thereof.

55 The invention will be readily understood by

3

reference to the following detailed description when read in connection with the accompanying drawing, in which

Figure 1 is an end view partly in section of a preferred embodiment of the invention; and

Figure 2 is a front elevation of a machine equipped with a plurality of units comprising drying and collecting devices according to the preferred embodiment of the invention.

In the drawing, 1 is a framework upon which is supported a tank 2 containing a coagulating and regenerating bath 3 of suitable composition. Viscose or other fiber-forming material is extruded into bath 3, through a spinneret, in the form of a single filament or a plurality of filaments 4. The thread 4 is drawn from the bath by means of draw-off roller 5, and is then passed to a thread-storing, thread-advancing device or reel 7, through a trough 6 containing a suitable treating liquid. Thread-advancing, thread-storing means 7 may be driven at a speed such that the thread is given a stretch between it and draw-off roller 5. On thread-advancing reel 7, the thread may be sprayed or bathed with a liquid or liquids from a pipe or a plurality of separate pipes extending across the spinning machine, such as pipes 8, 8', having nozzles or the like therein, such as shown at 8, 8'. The thread is then continuously forwarded over the smooth surface of a heating element 10, which may be interiorly heated by any suitable means, and dried during its travel thereover. A tension responsive means is provided, having a tension responsive element such as pulley 11, preferably constructed of a light weight material such as "Bakelite," under which the dried thread passes, after leaving the drying zone, and which is thus suspended in the loop formed in the material. After passing through the loop, the thread is advanced to the collecting device 12, through the traversing thread guide 13.

The tension responsive means also includes an arm 14, one end of which is mounted on spindle 15, and the other end of which is secured for rotation with shaft 16 by collar 17. Shaft 16 which is supported on frame work 1 by bracket 24, also has mounted thereon a transverse arm forming two oppositely extending rods 18 and 19. Rod 18 carries a screw-type adjustable balance weight 20. Rod 19 carries a pulley 21 which normally rests lightly upon an endless belt 22 which is supported by rollers 23, and which in turn rests upon pulley 26 which is rotatably mounted between bearings 27 and 28 on shaft 25, in direct-drive relation with the collecting device 12. The speed of the collecting device 12 is controlled by the pressure exerted by pulley 21 on belt 22, and the resulting pressure of belt 22 on pulley 26.

As the speed of collecting on device 12 tends to increase, because of increase in the diameter of the package, the length of material suspended in the vicinity of the drying zone tends to be shortened. Any such shortening will immediately cause pulley 11 to rise, actuating arm 14, which will in turn raise pulley 21 from belt 22, diminishing the pressure of the belt on pulley 26, thus decreasing the speed at which the collecting device 12 is driven, and automatically restoring the material suspended in the vicinity of the drying zone to its previous predetermined length.

On the other hand, if for any reason an undesirably large amount of slack occurs in the material suspended in the vicinity of the drying zone, pulley 11 is lowered, actuating arm 14 so as

4

to cause an increase in the pressure exerted by pulley 21 on belt 22, and hence of belt 22 on pulley 26, which results in a corresponding increase in the speed at which collecting device 12 is driven. The undesirable slack in the suspended material is immediately taken up and the undesired excess tension is automatically removed.

The supports 23 for endless belt 22 are rotatable, but otherwise fixed, and are preferably so positioned with respect to the tension responsive means that each of the individual drying and collecting means comprising one of a plurality of units of the machine may be independently adjusted without interference with any of the remaining units.

The invention affords a delicately responsive means for automatically and substantially continuously machining a light but constant tension on running lengths of filamentary material during travel thereof over the heating element and thus insures freedom for uniform shrinkage of the material throughout its entire length. Filamentary material thus dried possesses uniform residual shrinkage capacities along the length thereof, as well as uniform dye affinities, and is especially desirable for the fabrication of textile goods of superior quality.

Instead of drying the thread or the like by passing it over the surface of an interiorly heated element, the thread may be dried by passing it through a heated enclosed chamber or by subjecting it to a high frequency electric current induced longitudinally or horizontally thereof, after which the material is formed into a loop and collected as described above. The heating element shown has the advantage that high temperatures may be utilized, thus permitting rapid drying of the traveling filamentary material.

Numerous changes and modifications may be made in the process and apparatus herein described without departing from the spirit and scope of the invention, which is not to be limited except as defined by the appended claims.

I claim:

1. In an apparatus for drying filamentary material of indefinite length, a smooth stationary heated surface, means for continuously advancing the material at a substantially uniform rate of speed over and in contact with the heated surface through a path having a substantially straight undeviating portion which comprises the heated surface and a loop portion at the discharge end of the straight portion, means adjacent the end of the path for collecting the material in the form of a wound package, means for varying the speed of the collecting means, and a tension responsive element in the loop for controlling the speed varying means and maintaining the length of the material moving freely in the straight and loop portions of the path substantially constant to permit free uniform lengthwise contraction of the material during drying.

2. In an apparatus for drying filamentary material of indefinite length, a smooth, stationary heated surface, means for continuously advancing the material at a substantially uniform rate of speed over and in contact with the heated surface through a path having a substantially straight undeviating portion which comprises the heated surface and a loop portion at the discharge end of the straight portion, means adjacent the end of the path for collecting the material in the form of a wound package, means for varying the

speed of the collecting means, and a tension responsive element suspended in the loop and associated with the speed varying means for correlating the speed of the collecting means with the length of the material moving freely in the straight line and loop portions of the path to permit free uniform lengthwise contraction of the material during drying.
